UNITED STATES PATENT OFFICE

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA

COKING RETORT OVEN

Application filed January 2, 1923, Serial No. 610,107. Renewed April 1, 1930.

- This invention comprehends improvements of general utility in the coking retort oven art; and also comprehends certain improvements especially applicable to coking retort 5 ovens of the longitudinal-regenerative type in which the regenerators extend parallel with the longitudinal axis of the oven battery and transversely in respect of the coking chambers and the heating walls.
- 10 The invention has for objects the provision of a coking retort oven having, as important characteristics: The embodiment of the cross-over flow-duct principle exemplified in my prior Letters Patent of the United States No. 15 1,374,546, for coking retort-oven, dated April 12, 1921, in a coke oven battery with longitudinal regenerators; and, as a further feature, the employment of the cross-over duct principle in a longitudinal regenerative coke 20 oven that is alternatively operable, according to the combination oven principle, for being fired with its own relatively rich distillate gas, or with an extraneously derived relatively lean gas, such as ordinary producer 25 gas or blast furnace gas.
- By the invention, there is provided a flue construction that permits a considerable reduction not only in the length but also in the cross sectional dimensions of the horizontal or 30 bus flues located at the top of the vertical flame flues and connecting a plurality of the latter with each other; and, as a feature that may be secured by the above structural improvements, a novel system of control of the 35 flow through the flame flues of the heating walls, permitting flow in the same direction through all the flame flues of each heating wall, with the result that all of the flame flues of each heating wall are either simultaneously 40 burning or simultaneously operating as downflow flues for carrying away the waste gases to outflow operating regenerators.
- With regard to the novel flue construction, for example, a pair of horizontal flues in each 45 heating wall may be substituted for the usual single horizontal flue which extends from end to end of the heating wall. With a pair of separate horizontal flues, each member of the pair need communicate with only approximately half the total number of flues of the
- heating wall and consequently the dimensions of each flue may be considerably decreased because of the consequent reduction in the volume of flow which must be maintained through the horizontal flue. The above stated 55 reduction in size of the horizontal flues is an important advantage for the reason that it enables a considerable thickening and strengthening of the walls of the oven structure in the region of the horizontal flues. 60 Moreover, the improved flue construction permits an increase in the height of the flame flues, with a corresponding increase in the height of the coking chambers so that the latter may be made narrower in width, a development greatly facilitating the coking of 65 high volatile coals, and yet having adequate provision for taking care of the increased volume of combustion products, without making it necessary to enlarge the horizontal flue 70 dimensions to sizes consistent with adequate strength of the wall construction in the region of such flues. The flue construction of the invention is furthermore of great importance in oven batteries fired with extraneously-derived gas, such as producer gas, since the employment of such gas results in an increased 75 volume of combustion products and adequate flue spaces must be provided to collect and feed to the downflow operating 80 flues this increased volume of combustion products. By the invention, the flue construction may be adequately accommodated to such increased volume of combustion products, without introducing elements of weakness 85 into the wall structure.
- In addition to the objects cited above, the invention has for other objects such other improvements or advantages in construction and operation as are found to obtain in the 90 structures and devices hereinafter described or claimed.
- In the accompanying drawings, forming a part of this specification, and showing for purposes of exemplification, a preferred form 95 and manner in which the invention may be embodied and practised, but without limiting the claimed invention to such illustrative instance or instances:

Figure 1 is a crosswise vertical section 100

Figure 13 is a horizontal section taken on the line F—F of Figure 6.

The same characters of reference designate the same parts throughout the several views of the drawings.

As illustrated in the drawings, the invention is incorporated in one form in a battery of the "coke oven" type and, in further forms, in a combination coke oven battery, i. e., a battery having provision for being operated either with producer gas as a fuel, or with coke oven gas burned in an atmosphere of ordinary preheated air, such as is utilized in ordinary coke ovens, or with coke oven gas burned in an atmosphere containing both air and a neutral gaseous diluent which is introduced into the flame flues separately from the air.

For convenience, the present description will be confined to the present illustrated embodiment of the invention; the novel features and improvements made by the invention are susceptible of other applications,

such, for example, as ordinary so-called "gas ovens" employing producer gas as a fuel; hence, the scope of the invention is not confined to the specific use and specific embodiment herein described as an illustrative example.

Referring to the drawings, there are illustrated views of a coke oven battery or plant of the by-product type, having features above specified; said oven battery embodies in its construction a plurality of crosswise elongated heating walls 11, 11 and a plurality of intermediate crosswise elongated vertical coking chambers 12, 12. The heating walls 11 form the side walls of the respective coking chambers 12, as shown more particularly in Figs. 2, 4 and 6, and, in the present instance, are directly supported by the heavy supporting or pillar walls 13, 13 which extend longitudinally of the battery and are located, as shown in Figs. 1, 3 and 5, beneath the respective heating walls 11, 11 and coking chambers 12, 12. These pillar walls, hereinafter described, collectively form the main support for the entire superstructure of the oven battery and are themselves supported upon a flat mat or platform which constitutes the sub-foundation on which the entire battery rests. The coal to be coked is charged into the several coking chambers or ovens through charging holes 14 located in the top 15 of the oven battery and positioned directly above the ovens or chambers 12, as shown in Figs. 1 and 2. These charging holes 14 are equipped with the usual removable covers, which are removed during charging of the individual ovens or coking chambers and are placed in position to close the tops of such coking chambers during the entire coking or distilling operation. The gases of distillation pass from the tops of the several coking chambers 12 through gas outlets 16 and thence through ascension pipes (not shown) into the usual gas collecting mains which carry the distillation products to the by-product recovery apparatus.

Heat for coking the charges of coal in the several ovens or chambers 12 is derived from the heating walls 11, which, as above mentioned, extend crosswise of the battery at the sides of the coking chambers. Referring now more particularly to Figs. 2, 4 and 6, each heating wall 11 is constituted of a plurality of flame or combustion flues 17. The flame flues of each heating wall are, in accordance with the invention, operatively disposed into a single group, that is to say all of the flues of each heating wall operate concurrently as upflow or downflow flues, as will be herein-after more fully explained. When the flame flues on one side of a coking chamber are burning, that is to say, operating for up-flow, the flame flues on the opposite side of the same coking chamber are operating for down-flow to permit exhaust of the waste gases.

Consequently heating is maintained continuously from end to end on one side of a charge of coking coal in each coking chamber, the heat being applied to the full length of one side of such charge during an entire period, and, then, after reversal, being applied to the full length of the opposite side of the charge, until a subsequent reversal is effected.

The longitudinal regenerators 18 of the battery are located at a lower level than the aforesaid heating walls 11 and the coking chambers 12, and, in the present instance, extend in parallelism between the longitudinal pillar walls 13. These pillar walls are constituted of the middle pillar wall 13a, located in the middle lengthwise vertical plane of the battery, the opposite side pillar walls 13b, and the mediate pillar walls 13c which are respectively located between the opposite side pillar walls 13b and the middle pillar walls 13a. As shown in Figures 2, 4 and 6, there are also provided crosswise partition walls 22 which extend beneath alternate heating walls 11 from the opposite sides of the battery to the middle pillar wall 13a. This construction provides four series of longitudinally extending regenerators beneath the coking chambers and heating walls. According to the form of invention shown in Figs. 1 and 2 the two interior series of longitudinal regenerators which are located between the middle pillar walls 13a and the mediate pillar walls 13c may function concurrently as waste gas regenerators W, while the two side series of longitudinal regenerators, which are located between the mediate pillar walls 13c and the side pillar walls 13b, function concurrently as air regenerators A. Each regenerator 18 is a chamber containing open brick work, commonly called checker work, and indicated at 20, with a distributing sole channel 21 underneath such checker work, the channels forming the soles of such chambers and opening up into the checker work. The regenerators are heated, in alternation, by the hot combustion products that draw off from the flame or combustion flues hereinbefore mentioned and then impart such heat to the medium that they feed into these flame flues.

In the present embodiment of the invention, the entire series of flame flues 17 of each heating wall 11 is either burning or operating for downflow to convey waste products to the regenerators beneath and consequently the longitudinal regenerators which are connected with a heating wall operate concurrently for flow in the same direction and in the same manner. The reversal in flow through the flame flues 17 on opposite sides of a coking chamber, and their communicably connected regenerators may thus be said to take place longitudinally of the oven battery, instead of transversely thereof, as has heretofore been a common practice in this art.

The reversal of the oven is effected at the end of an operating period determined by practice, and by means of any preferred type of reversing mechanism. The function of such reversal is as follows: The regenerators that prior to the reversal operated as inflow regenerators become outflow regenerators, and the outflow operating regenerators become inflow operating regenerators; the upburning series of flue switches functions with the downburning series of flues of the next adjacent heating wall, and the supply of gas is turned off from the previously upburning flues and turned on into the mains of the previously downburning flues.

Each flame flue 17 of each heating wall has at its top a port or opening 24 for draft and the passage of combustion products or waste gas from the flame within the flue. These ports 24 open up into horizontal or bus flues 25 formed in the heating walls and connecting all of the vertical flues that communicate with such horizontal flues 25 by means of the ports 24. According to the invention, there are in each heating wall a plurality of, in the present instance two, of such horizontal flues 25 positioned end to end with respect to each other and respectively located on opposite sides of the central dividing line L. By reason of the fact that there is a plurality of such horizontal flues 25, these flues 25 are not required to be of so great capacity as that necessary in present practice and consequently the cross-sectional area of each horizontal flue 25 may be materially reduced proportionately with the length of such flue, with the result that the thickness and strength of the heating walls are substantially increased in the region of the horizontal flues. Moreover, because of the fact that each horizontal flue 25 communicates with a substantially reduced number of vertical flues, in the present instance half of the flues of a heating wall, uniformity in distribution of the flow through the vertical flues and the communicating regenerators is greatly promoted.

As shown, the two horizontal flues 25 of each heating wall are communicably connected by means of cross-over duct means or passageways 26 respectively with the corresponding horizontal flues of one of the next adjacent heating walls. These channels 26 preferably open up into substantially the middle portions of their respective connected flues 25, and extend longitudinally of the oven battery. Thus the entire flow from a heating wall, within the flues of which combustion is being maintained, passes through and downwardly through all of the flues of the next adjacent heating wall and each reversal operation is accompanied by a reversal in direction in flow of all of the flues of each heating wall.

The drafts through the ports 24 may be regulated by means of the usual movable

dampers or sliding bricks 27, positioned in the ordinary way in the bottoms of the horizontal flues 25 and adapted to be reached by access flues 28 which extend from the top of the horizontal flues 25 in each heating wall 5 to the top 15 of the battery, there being an access flue positioned over each flame or combustion flue of each heating wall.

Extending crosswise of the battery and located beneath the heating wall 11 thereabove, is a pair of gas supply channels 29 and 30. These channels 29 and 30 are for the purpose of supplying coke oven gas to the several flame flues on each side of the central line L, 10 and to accomplish this end, the channel 29 15 communicates with the individual flues 17 on the near side of said line L by means of ducts 31 that lead from such channel 29 individually into the bottoms of individual flues; and the channel 30 which supplies the several 20 flues that are located on the far side of the before-mentioned dividing line L, communicates therewith by means of similarly connecting ducts. Within the several ducts are 25 disposed the usual nozzles 32. The supply of coke oven gas to the respective channels 29 and 30 is derived from coke oven gas mains of the usual type and respectively located on the opposite sides of the battery and extending 30 longitudinally therealong. Suitable means is provided for admitting or cutting off the supply of gas with respect to each pair of channels 29 and 30, it being understood that the gas supply is either concurrently 35 maintained or concurrently shut off from both channels of each pair.

With the above described construction, each heating wall is constituted of two groups M and N of vertical combustion flues and the groups M, N of the alternate heating walls K are connected by the hereinbefore described crossover duct passages with the corresponding groups of flues of the intermediate heating walls I. According to 40 the battery construction of the "coke oven" type shown in Figs. 1 and 2 the individual regenerators of the opposite side series A are connected by ducts 41 with horizontal distributing flues 42 that extend in pairs beneath the combustion flues of the intermediate heating walls I. The respective distributing flues 42 of each pair extend inwardly to the central longitudinal vertical plane L and correspond with the groups M, N of the 45 combustion flues of the intermediate heating walls. Each distributing flue 42 is connected with the individual combustion flues of the corresponding group by ports or ducts 43. In like manner, the individual regenerators of the two inside series W are 50 connected by ducts 51 with horizontal distributing flues 52, the latter being connected by similar ports or ducts 53 with the individual combustion flues of the groups M, N of the 55 alternate heating walls K.

In operating the battery illustrated in Figs. 1 and 2, a supply of coke oven gas is maintained in the channels 29 and 30 which feed the upburning flues. Assuming that the intermediate heating walls I are operating 70 for inflow combustion and the alternate heating walls K for downflow of waste gas, the two side series of the regenerators operate as inflow air regenerators A, while the two inside series of regenerators operate as outflow waste gas regenerators W. On reversal 75 of the flow, the inflow operating regenerators and flues become outflow regenerators and flues and concurrently the outflow regenerators and flues become inflow regenerators and flues.

The battery illustrated in Figs. 3 and 4 is designed for operation on the "combination oven" principle, that is to say alternatively with the employment of the coke oven gas 80 as the oven fuel, or with a special generator gas, such as producer gas. Referring to Figs. 3 and 4 the heating walls are grouped into alternate pairs K' and intermediate pairs I'. All the flues of the several pairs I' operate for flow in the same direction while the flues of the alternate pairs K' are operating for flow in the opposite direction, as indicated by the arrows in Fig. 4. The regenerators of the inside series and the side series 85 are grouped into pairs crosswise of the battery, each pair being constituted of a side regenerator and an inside regenerator, as shown in Fig. 3. The intermediate pairs of regenerators I' correspond with and serve the intermediate pairs of heating walls I'; similarly the alternate pairs of regenerators K' correspond with and serve the alternate pairs of heating walls K'. Each regenerator is connected with all the flues of its corresponding groups M or N of both heating walls of its corresponding pair of heating walls. The side regenerators of the intermediate and alternate groups I' and K' are 90 respectively connected by ducts 61 with horizontal distributing flues 62 which extend under the coking chamber between the individual heating walls of the intermediate and alternate pairs I' and K'. These distributing flues 62 are respectively connected with the groups M or N of the combustion flues of both heating walls of the corresponding intermediate or alternate pairs I' or K' by ducts or ports 63. The individual regenerators of both inside series which make up the alternate and intermediate pairs I' and K' of regenerators are respectively provided with pairs of ducts 71 that lead to individual horizontal distributing flues 72. The two distributing flues 72 corresponding to each 95 individual regenerator of the inside series are respectively connected by ducts 73 with the groups M or N of combustion flues of the two heating walls that make up the pair corresponding to that regenerator. With the 100

above described construction, each flame flue 17 is connected with adjacent separate regenerators of a pair I² or K², in which the flow is maintained concurrently in the same direction, that is to say that both said regenerators are either operating for inflow or for outflow.

The operation of the battery, when employing a special generator gas, such as ordinary producer gas as the fuel, is as follows: The supply of coke oven gas to the coke oven gas main and to all of the coke oven gas channels 29, 30 is cut off. A supply of producer gas is permitted to flow into the producer gas regenerator P, such as are operating for inflow, and passing through said regenerators is preheated before being delivered into the burning flame flues. During the inflow of producer gas through such generators P waste gas from the downburning flues is flowing out through the other regenerators W. In the regenerators A inflow of air is maintained and passing upwardly through such regenerators finally enters the burning flame flues to support the combustion of the producer gas that is delivered thereto by the regenerators P. On reversal of the flow, the inflow operating regenerators become outflow regenerators and consequently the outflow operating regenerators become inflow regenerators.

In operating the battery with coke oven gas in the ordinary manner, the supply of producer gas to regenerators P is shut off and air is permitted to flow into such regenerators in place of the producer gas. During coke oven gas operation, a supply of coke oven gas is maintained in the channels 29 and 30 which feed the upburning flues. The reversing mechanism is operated at each reversal to place all of the inflow operating regenerators in communication with the outer air and concurrently all of the outflow operating regenerators in communication with the exhaust. A further mode of operation is with coke oven gas as a fuel, combined with a supply of neutral gaseous diluent to the upburning flues. In so operating the battery, the supply of producer gas is turned off and the supply of coke oven gas is turned on. Instead however of permitting air to flow into regenerators of the series P that serve for producer gas, during the latter operation, waste gas is permitted to flow into such regenerators and be delivered thereby to the upburning flame flues. The admission into each of the upburning flues of a supply of the neutral gaseous diluent, such as waste gas, is effective to lengthen greatly the flames within such flues and to prevent the localization of the hottest flame temperature in the extreme lower portions of the flues.

A further type of "combination oven" battery is illustrated in Figs. 5 and 6. This embodiment of the invention is substantially

the same as that disclosed in Figs. 3 and 4, with the exception of the arrangement and grouping of the regenerators. Instead of grouping the producer gas and air regenerators crosswise of the battery, so that alternate pairs of such regenerators operate for inflow, while the intermediate pairs are operating for outflow, the producer gas regenerators P alternate with the air regenerators A, in the series of regenerators that extends longitudinally of the battery structure. With this arrangement all the regenerators of both side series operate for inflow, while, concurrently, all the regenerators of both the inside longitudinal series are operating for outflow as waste gas regenerators W, and vice versa. As shown, each regenerator A of the outside series is connected by a duct 81, distributing channel 82 and ducts 83 with a group of flame flues M or N of two adjacent heating walls such as the intermediate pair I'. The regenerators P of the outside series are each connected by a pair of ducts 91, distributing flues 92 and ducts 93 with one heating wall of each adjacent intermediate pair I. Each regenerator P of the inside series is connected by a duct 101, distributing channel 102 and ducts 103 with a group of flame flues M or N of an alternate pair K. The regenerators A of the inside series are each connected by a pair of ducts 111, distributing flues 112 and ducts 113 with one heating wall of each adjacent alternate pair K. With this arrangement, each pair of inflow-operating heating walls has flow duct connections with both air and producer gas regenerators, and the outflow-operating heating walls have flow duct connections with waste gas regenerators. The operation of the battery shown in Figs. 5 and 6 is substantially the same as that hereinbefore described in connection with Figs. 3 and 4 and has the same alternative modes of operation.

In all forms of the invention, there is provided a substantially independent structure for the flow of the heating gases on both sides of the longitudinal central plane of the battery. This arrangement permits independent control of the flow of the heating gases on the respective sides of the battery structure. Inasmuch as the horizontal ovens taper in width from the pusher end at one side of the battery to the coke end at the other side, the arrangement of the invention provides the important advantage that the volume of gases required to heat the charge in the relatively narrow end of the coking chamber may be accurately regulated without reducing the greater volume of heating gases required for the relatively thicker charge at the wider coke end of the chamber. Consequently uniformity of temperature and heating of the charge is greatly promoted throughout the battery structure. At the same time such regulation as will avoid waste of heat is pro-

5 moted. The grouping of the flame flues into groups M, N with the substantially independent regenerative connections to each group permits one end of a heating wall to be operated for upflow, while, if desired, the opposite end of the heating wall may be concurrently operated for downflow.

10 The invention as hereinabove set forth may be variously embodied within the scope of the claims hereinafter made.

15 I claim:

1. In a coking retort oven, in combination: a plurality of coking chambers alternating with substantially similar heating walls contiguous to such coking chambers and respectively constituted of vertical combustion flues; horizontal flues in each heating wall and respectively connecting a plurality of the combustion flues of their respective heating walls; the horizontal flues of a heating wall being also communicably connected with the corresponding horizontal flues of an adjacent heating wall; several main supporting walls below the coking and heating chambers and extending longitudinally of the oven and forming lengthwise of the oven tunnel structures and individually regulable and reversible regenerators between the adjacent supporting walls, each regenerator communicating with flues of both of two heating walls on opposite sides of a coking chamber and connected in pairs with combustion flues of a single heating wall; substantially as specified.

2. In a coking retort oven, in combination: a plurality of coking chambers alternating with substantially similar heating walls contiguous to such coking chambers and respectively constituted of vertical combustion flues; horizontal flues in each heating wall and respectively connecting a plurality of the combustion flues of their respective heating walls; the horizontal flues of a heating wall being also communicably connected with the corresponding horizontal flues of an adjacent heating wall; several main supporting walls below the coking and heating chambers and extending longitudinally of the oven and forming lengthwise of the oven tunnel structures and regenerators between adjacent supporting walls and connected with said combustion flues, the regenerators being arranged in longitudinal series, with the inflow and the outflow regenerators in different longitudinal series and with each series of inflow regenerators constituted of air regenerators and alternate producer gas regenerators; substantially as specified.

3. In a coking retort oven, in combination: a plurality of coking chambers alternating with flued heating walls respectively constituting the opposite side walls of said coking chamber, the flues of the heating walls being communicably connected with each other by duct means extending over the top of the cok-

10 ing chamber, reversible means for maintaining combustion in alternation in said heating walls, the connections being such that the exhaust gases produced by the combustion in one heating wall are drawn off through the other, several main supporting walls below the coking and heating chambers and forming lengthwise of the oven tunnel structure and reversible regenerators between the adjacent supporting walls and disposed in series extending longitudinally of the oven and respectively connected with said heating walls; the inflow regenerators and the outflow regenerators being in different longitudinal series substantially as specified.

4. A coking retort oven battery comprising coking chambers alternating with flued heating walls, said heating walls being communicably connected in pairs by ducts extending across the intervening coking chambers, and regenerators disposed in tunnel structures that extend longitudinally of the battery and operatively disposed in reversible inflow and outflow groups respectively connected with the flues of said heating walls, and in which the arrangement specified is substantially duplicated on both sides of the central longitudinal plane of the battery, substantially as specified.

5. A coking retort oven battery comprising coking chambers alternating with flued heating walls, said heating walls being communicably connected in pairs by ducts extending across the intervening coking chambers, and regenerators disposed in tunnel structures that extend longitudinally of the battery and operatively disposed in reversible inflow and outflow groups respectively connected with the flues of said heating walls, and in which the connections are such that some of the chambers may be heated by flame along both sides simultaneously in alternate working periods while other chambers are heated by flame first on one side and then on the opposite side in successive working periods, substantially as specified.

6. A coking retort oven battery comprising coking chambers alternating with flued heating walls, said heating walls being communicably connected in pairs by ducts extending across the intervening coking chambers, and regenerators disposed in tunnel structures that extend longitudinally of the battery and operatively disposed in reversible inflow and outflow groups respectively connected with the flues of said heating walls, and in which the inflow and outflow regenerators are respectively arranged in alternate rows transversely of the tunnels and are respectively connected by ducts to the flues of the respective heating walls of communicably connected pairs, substantially as specified.

7. A treating retort battery comprising treating chambers alternating with flued heating walls, the heating walls being com-

10 8. A treating retort battery comprising treating chambers alternating with flued heating walls, the heating walls being communicably connected in pairs, one of the walls of each pair serving for inflow while the other serves for outflow, the inflow and outflow serving walls of adjacent pairs being arranged respectively next to each other, and regenerators, each respectively communicably connected with the respective adjacent heating walls of adjacent pairs, substantially as specified.

15 9. In a coking retort oven, in combination: a series of horizontal coking chambers alternating with substantially similar heating walls contiguous to said coking chambers and respectively comprising vertical combustion flues operable in alternation for upflow combustion and downflow of combustion products; horizontal collecting flow duct means in each heating wall and respectively connecting a plurality of the combustion flues of their respective heating walls at their upper ends; the horizontal flow duct means of a heating wall contiguous to one of said coking chambers being also communicably connected with the horizontal flow duct means of one of the heating walls on the opposite side of said one of said coking chambers by cross-over duct means crossing over said one of said coking chambers; several main supporting walls below the coking chambers and heating walls and extending longitudinally of the oven and forming lengthwise of the oven arched tunnel structures; and regenerators between the adjacent supporting walls and arranged in two longitudinal series disposed side-by-side transversely of the oven and operable in alternation with each other for inflow and outflow; the regenerators of each of the longitudinal series of regenerators being communicably connected with vertical combustion flues of some of the heating walls in the portions of the oven structure above them and being also communicably connected with vertical combustion flues of some of the heating walls in the portions of the oven structure above regenerators of the other series of regenerators by conduit devices comprising channel means respectively extending lengthwise of said coking chambers and heating walls below the plane of the bottoms of the vertical flues with which they communicate and above the regenerators below the plane of the vertical flues with

which they communicate and above the regenerators below the same vertical flues.

10 11. In a coking retort oven, in combination: a series of horizontal coking chambers alternating with substantially similar heating walls contiguous to said coking chambers and respectively comprising vertical combustion flues operable in alternation for upflow combustion and downflow of combustion products; horizontal collecting flow duct means in each heating wall and respectively connecting a plurality of the combustion flues of their respective heating walls at their upper ends; the horizontal flow duct means of a heating wall contiguous to one of said coking chambers being also communicably connected with the horizontal flow duct means of one of the heating walls on the opposite side of said one of said coking chambers by cross-over duct means crossing over said one of said coking chambers; regenerators arranged in two longitudinal series disposed side-by-side transversely of the oven and operable in alternation with each other for inflow and outflow and respectively extending transversely of and below the coking chambers and heating walls; the regenerators of each of the series being communicably connected with vertical combustion flues of some of the heating walls in the portions of the oven structure above them and being also communicably connected with vertical combustion flues of some of the heating walls in the portions of oven structure above regenerators of the other series of regenerators by conduit devices comprising channel means respectively extending lengthwise of said coking chambers and heating walls below the plane of the bottoms of the vertical flues with which they communicate and above the regenerators below the same vertical flues.

15 12. In a coking retort oven, in combination: a series of horizontal coking chambers alternating with substantially similar heating walls contiguous to said coking chambers and respectively comprising vertical combustion flues operable in alternation for upflow combustion and downflow of combustion products; horizontal collecting flow duct means in each heating wall and respectively connecting a plurality of the combustion flues of their respective heating walls at their upper ends; the horizontal flow duct means of a heating wall contiguous to one of said coking chambers being also communicably connected with the horizontal flow duct means of one of the heating walls on the opposite side of said one of said coking chambers by cross-over duct means crossing over said one of said coking chambers; regenerators arranged in two longitudinal series disposed side-by-side transversely of the oven and operable in alternation with each other for inflow and outflow

and respectively extending transversely of and below the coking chambers and heating walls, the regenerators of each of the series being communicably connected with vertical combustion flues of some of the heating walls in the portions of the oven structure above them and being also communicably connected with vertical combustion flues of some of the heating walls in the portions of oven structure above regenerators of the other series of regenerators by conduit devices comprising channel means respectively extending lengthwise of said coking chambers and heating walls below the plane of the bottoms of the vertical flues with which they communicate and above the regenerators below the same vertical flues; and each series of regenerators, when operable for inflow, comprising air regenerators and fuel gas regenerators with the air regenerators and the gas regenerators arranged side-by-side in a single row.

12. A coke oven as claimed in claim 10 and in which each series of regenerators comprises, when operable for inflow, air regenerators and fuel gas regenerators.

13. A coking retort oven battery comprising, in combination: a series of alternate horizontal coking chambers and vertically flued heating walls therefor arranged laterally of each other in a row, and regenerators arranged in two longitudinal series disposed side-by-side transversely of the battery below the coking chambers and heating walls, one of said series being operable for inflow as air and gas regenerators while the other series operates simultaneously for outflow as waste gas regenerators, and reversely, and the regenerators of each series being in communication with vertical flues that are above said series and also communicably connected by feed-ducts with distributing channels that extend lengthwise of the coking chambers and over the regenerators of the other series of regenerators and are directly communicably connected with vertical flues that are above said series of regenerators, so that regenerative fuel-gas and air inflow and waste-gas outflow may be effected concurrently in vertical flues above both series of regenerators simultaneously and so that counterflow of fuel-gas and waste-gas in regenerators alongside each other in a series lengthwise of the battery is avoided; and in which the aforesaid feed-ducts of the regenerators of each series of regenerators lead directly from their respective regenerators into the distributing channels above the other series of regenerators, and the aforesaid feed-ducts of the regenerators of one of the two series of regenerators and the adjacent counter-current feed-ducts of the concurrently reverse-flow regenerators of the other of the two series of regenerators are both located in massive masonry at the top of the aforesaid partition-wall that is between said two series of regenerators.

generators of the other of the two series of regenerators.

14. A coking retort oven battery comprising, in combination: a series of alternate horizontal coking chambers and vertically flued heating walls therefor arranged laterally of each other in a row, and regenerators arranged in two longitudinal series disposed side-by-side transversely of the battery below the coking chambers and heating walls and with a massive partition-wall extending lengthwise of the battery between the two series of regenerators, one of said series being operable for inflow as air and gas regenerators while the other series operates simultaneously for outflow as waste gas regenerators, and reversely, and the regenerators of each series being in communication with vertical flues that are above said series and also communicably connected by feed-ducts with distributing channels that extend lengthwise of the coking chambers and over the regenerators of the other series of regenerators and are directly communicably connected with vertical flues that are above said other series of regenerators, so that regenerative fuel-gas and air inflow and waste-gas outflow may be effected concurrently in vertical flues above both series of regenerators simultaneously and so that counterflow of fuel-gas and waste-gas in regenerators alongside each other in a series lengthwise of the battery is avoided; and in which the aforesaid feed-ducts of the regenerators of one of the two series of regenerators lead directly from their respective regenerators into the distributing channels above the other series of regenerators, and the aforesaid feed-ducts of the regenerators of one of the two series of regenerators and the adjacent counter-current feed-ducts of the concurrently reverse-flow regenerators of the other of the two series of regenerators are both located in massive masonry at the top of the aforesaid partition-wall that is between said two series of regenerators.

In testimony whereof I have hereunto set my hand.

JOSEPH BECKER.
